ENGINE

Ignac Sklenár, Paris, France

Application November 15, 1938, Serial No. 240,515

4 Claims. (Cl. 123—44)

This application is a continuation-in-part with respect to my copending application Serial No. 28,195, filed June 24, 1935, now Patent Number 2,153,727 of Apr. 11, 1939.

The present invention relates to engines and has particular reference to internal combustion engines of what may conveniently be termed bi-rotary type. By the term bi-rotary as herein employed is meant that general type or class of engine the characteristic feature of which is an annular ported valve member encircling the outer ends of a bank of radially arranged cylinders, with the valve member and the cylinder bank mounted to have relative rotary movement and with flow of cylinder gases controlled by ports in the valve member and in the outer ends of the cylinders which pass into and out of communication with each other due to the relative rotary movement between the parts. Within this general class of engine either the valve member or the cylinder bank may be rotationally stationary or both parts may have rotational movement, the essential feature being relative rotary movement between these parts. Also within this general classification various different combustion cycles may be employed.

In certain of its aspects the present invention is particularly advantageous in connection with Otto cycle operation on the four stroke cycle principle and the invention will accordingly hereinafter be described and illustrated in its application to this particular form of engine, it being understood however, that such description is by way of example only and is not limiting with respect to the scope of the invention, which is defined in the appended claims.

The general object of the invention is to improve upon the efficiency of operation of bi-rotary engines and to this end the invention in one of its aspects contemplates the provision of novel means whereby the timing of the opening and closing events of intake and exhaust, particularly intake, with respect to the cycle of operation of the engine, may be altered to provide more efficient charging of the engine cylinders regardless of variations in speed of operation of the engine than has heretofore been attainable. In another of its aspects the invention contemplates the improvement of combustion efficiency and certainty of ignition by the provision of novel means for ensuring the presence of fresh gases in the vicinity of the igniting device at the time of each ignition and for minimizing dilution of the fresh charge inducted into any given cylinder with products of combustion resulting from

the combustion occurring in another and previously fired cylinder.

The manner in which the general objects and other and more detailed objects of the invention are obtained and the advantages to be derived from use of the invention may best be understood from a consideration of the ensuing portion of this specification, taken in conjunction with the accompanying drawings illustrative of the application of the invention to engine structure of the class under consideration.

Fig. 1 is a partial view in vertical section through the engine;

Fig. 2 is an enlarged vertical sectional view 15 on line 2—2 of Fig. 1;

Fig. 3 is an enlarged detail view in vertical section through a portion of the engine;

Fig. 4 is a view similar to Fig. 3 but showing the valve member in a different position of adjustment;

Fig. 5 is an enlarged detail view in vertical section of an ignition pocket venting means; and

Fig. 6 is a view similar to Fig. 5 of a slight modification.

25 Referring now more particularly to Figs. 1 to 3 of the drawings the engine illustrated is of bi-rotary type of known form and comprises an annular valve member indicated generally at 10 encircling a cylinder bank which in the present embodiment comprises a group of seven radially arranged cylinders 12. Preferably, but not necessarily, the valve member 10 is mounted to have no absolute rotational movement while the cylinder bank is mounted to rotate. In the embodiment illustrated the direction of relative rotation of the cylinder bank with respect to the valve member 10 is indicated by the arrow 14. Each of the cylinders 12 is provided with a piston 16 and in the embodiment illustrated the several 30 pistons are connected to a common crank pin 18 by means of a master connecting rod 20 and a number of link rods 22.

The desired operating phase relation between the relatively moving valve member, cylinder bank and crankshaft is maintained by suitable gearing interconnecting these major components of the engine, which gearing may take any one of a number of different well known forms and which need not be illustrated or described herein 35 in order for the present invention to be understood.

The annular valve member 10 provides a series of peripherally spaced exhaust passages 24 each terminating at the inner surface of the valve member in an exhaust port 26,

Member 10 is further provided with a plurality of peripherally spaced inlet passages 28 terminating at their inner ends in inlet ports 30 and at their outer ends in inlet manifold connections 32. Advantageously, as shown, the exhaust passages extend radially directly through the valve member while the inlet passages extend peripherally for some distance between their respectively offset ports 30 and manifold connections 32, the latter in the present instance being shown as opening laterally at one side of the valve member. With this arrangement of inlet and outlet passages the valve member is heated to minimum extent by the hot exhaust gases passing therethrough and cooling of this member is aided by the passage through the member of the relatively cool inlet gases.

Each of the cylinders is open at its outer end and carries a sealing element 34 which in the embodiment illustrated comprises an annular cuff-like member having a cylindrical portion 36 telescoped within a cylindrical neck 38 at the outer end of the cylinder and having a flange portion 40 the outer surface of which is spherically curved as indicated at 42 to provide a sealing surface. In addition to the sealing elements 34 the cylinder bank also carries an annular sealing ring which may be in the form of an integral one piece ring or may be built up of a series of segmental shoes 44 having suitable openings therein for the reception of the necks 38 of the cylinders and for the flange portions 40 of the sealing elements 34.

Packing rings 46 are advantageously provided between the sealing elements and the cylinder necks on the one hand and between the cylinder necks and the sealing ring on the other hand.

The inner surface 48 of the valve member is cylindrical and serves as a bearing for an annular control member 50 the outer surface of which is cylindrical and the inner surface of which is spherically curved as indicated at 52. Surface 52 is curved to the same radius as the outer spherically curved surfaces of the sealing elements 34 and the outer surface of the sealing ring, so that the sealing elements and the sealing ring move in sliding contact with the inner surface of the control member to provide a seal between the relatively moving parts to prevent the escape of cylinder gases.

The sealing ring 50 is mounted for turning movement relative to the valve member and in the embodiment illustrated the sealing ring is turned through a limited range of movement relative to the valve member by means of levers 54 pivoted at 56 to the valve member and provided at their inner ends with teeth 58 meshing with teeth 60 formed on flange portions 62 of the sides of the control member 50.

Member 50 is provided with a series of peripherally spaced ports 64 adapted to cooperate with the inlet ports 30 in the valve member and a second series of ports 66 adapted to cooperate with the exhaust ports 28.

In the engine illustrated, in which ignition is effected by means of high tension spark plugs, the valve member is provided with a series of peripherally spaced spark plug bores 68 in which are located the spark plugs 70. The control member 50 is provided with a series of similarly spaced ignition ports 72 to permit communication to be established between the spark plug bores and the interiors of the cylinders when the cylinder ports register with the ignition ports in the control member.

As will be observed from the drawings, the peripheral extent of each port 64 in the control member is less than the peripheral extent of the respectively cooperating inlet port of the valve member and likewise the peripheral extent of each port 66 in the control member is less than the peripheral extent of the respectively cooperating exhaust port of the valve member. On the contrary, the ports 72 in the control member 5 are advantageously have greater peripheral extent than the peripheral extent of the inner ends of the spark plug bores.

From Figs. 1 and 3, having particular reference to the inlet ports 30, it will be observed that if the direction of rotation of the cylinder bank relative to the valve member is as indicated by arrow 14, the instant of opening of the cylinder port for the admission of gases through the inlet passage 28 and valve port 30 will be determined by the position of the edge 74 of the port 64 in the control member and by shifting the control member peripherally with respect to the valve member by actuation of the levers 54, the timing of commencement of the inlet period may be altered with respect to the cycle of operation of the engine.

Likewise the timing of the end of the inlet period, which is controlled by the cylinder port passing the edge 76 of port 64, will be similarly delayed or advanced by shifting the position of the control member.

In like fashion the shifting of the control member will operate to alter the timing of the commencement and ending of the exhaust period, which is determined by the cylinder ports passing into and out of communication with the ports 66 of the control member.

It will thus be apparent that the shiftable control member provides for varying the timing of the opening and closing events for both inlet and exhaust and this in turn permits more efficient operation to be obtained throughout a wide range of speeds of operation than would be obtainable if the timing of these events remain constant.

It is well known that in high speed engines the gases in the manifolds show considerable inertia effect. This is particularly the case with the intake gases where the pressure differential between manifold pressure and the cylinder pressure during the intake period must of practical necessity be limited to a relatively low value so that high rates of gas acceleration are not possible. Experience has shown that in order to secure the most advantageous character of operation the opening and closing events of the intake in a high speed engine must take place much later than in a slow speed engine. For engines of automotive or other type which must be capable of operating over a wide speed range it is usually the practice to adjust these timing events for some intermediate speed and this compromise results in lower volumetric efficiency at low speeds and high speeds than would be the case if the timing of these events could be properly adjusted to the requirements of the low and high speeds of operation.

In so far as the timing of the opening and closing events of the exhaust are concerned a high speed engine theoretically requires an earlier exhaust opening and a later exhaust closing than a low speed engine. Practice however, shows that the time of exhaust opening is not critical. This is probably due to the fact that the critical pressure on either side of the exhaust orifice is ex-

ceeded by a considerable margin so that regardless of the operating speed the exhaust gases leave the cylinder with approximately the velocity of sound.

With the above in mind it will be evident that the provision of the shiftable control member in accordance with the present invention operates to permit the important factors of timing of the opening and closing events of the intake and also of the exhaust to be adjusted readily to compensate for variations in speed of operation of the engine.

As shown in Fig. 3 the control member is adjusted for low speed operation and as the engine speed is increased to a degree rendering retarding in the timing of the intake desirable, the control member may then be shifted to the left as viewed in Fig. 3 to effect retarding of both opening and closing of the intake relative to the cycle of operation of the engine.

Such movement of the control member operates to retard both the opening and the closing of the exhaust. As previously noted the opening of the exhaust should theoretically be advanced with increase in engine speed but as has been noted the opening of the exhaust is not a critical factor and variation of the timing of this event does not have the degree of effect on engine operation that the timing of the other events have. Consequently, in spite of the fact that with the arrangement described the change in timing of the exhaust opening is not in accordance with what is theoretically desirable, the improvement in operation effected by the retarding of the opening and closing of the inlet and the closing of the exhaust with increase in speed of operation greatly overbalances any more or less purely theoretical disadvantage arising from delaying opening of the exhaust with increase in speed of operation.

As previously noted the ports in the control member, which may conveniently be regarded as control ports, have less peripheral extent than their respectively cooperating ports in the valve member. With the ports proportioned in this manner it will be apparent that shifting of the position of the control ports will not affect the length of time in terms of crank travel of the intake or exhaust periods since the control ports will not be covered by any part of the wall of the valve member in any of the normal positions of adjustment of the control member.

In some instances it may be desirable to alter the length of either the intake or exhaust period or both when the timing is changed and to a certain practical extent the length of either or both of these periods in terms of crank travel may be varied with variation in the timing.

In order to illustrate how this may be accomplished there is shown in Fig. 4, an inlet control port 64a the peripheral extent of which is the same as the peripheral extent of the port 30 in the valve member.

By reference to Fig. 4 it will be observed that while in the position of the control member shown in the figure the theoretical length of the intake period is determined by the distance between the edges 74 and 76 of the control port, the actual practically effective length of time of the opening of the port is determined by the distance between the edge 78 of the valve member, which overlaps the edge 74 of the control member in the position shown, and the edge 76 of the control port. Thus, in the position of the ports shown, corresponding to low engine

speed, the really effective port opening occurs only when the edge 80 of the cylinder port passes edge 78 rather than edge 74. This is particularly true if the control member is of relatively very thin cross-section. It will be evident that as the control member is moved from the position in the figure, in order to delay timing of the opening and closing events, the distance of the clear port opening between edges 76 and 78 will increase so that the practical effect will be to increase the length of the intake period as the timing events of this period are retarded for increase in speed of engine operation.

From the above it will be apparent that by proper selection of the relative lengths of the port openings in the valve member and in the control member and proper location of the edges of cooperating ports with respect to each other, numerous variations in the character of timing and duration of both intake and exhaust periods is obtainable.

Because of the shifting of the control member relative to the valve member the ignition ports 72 in the control member advantageously have greater peripheral extent than the openings of the spark plug bores, in order to insure unobstructed communication between the place of ignition and the compression space of the cylinder in all positions of adjustment of the control member.

It will be evident that the control of the position of adjustment of the control member may be effected in any desired fashion, either manually or in response to one or more factors indicative of change of condition of engine operation requiring change of adjustment of this member.

In bi-rotary engines, one of the important practical advantages resides in the fact that the ignition means may be mounted in the valve member where it is exposed to combustion chamber pressures and temperatures substantially only for the instant required for ignition to be effected. This very obviously reduces the severity of service on spark plugs, the life of which is greatly extended as compared to what it would be if they were mounted in the cylinders.

Location of spark plugs or other igniting means in the valve member, however, introduces a certain operating difficulty which it is an object of the present invention to minimize or eliminate. The ignition means must evidently be placed in a recessed position in the valve member in order to permit the parts of the relatively rotating cylinder bank to pass the igniting means. Due to this recessed position required for the igniting means, a recess which for convenience may be referred to as an ignition pocket must necessarily be formed, particularly when the ignition means is in the form of the usual high tension spark plug having an outer metal shell and an inner core on which are mounted the electrodes of the plug and between which a cavity within the plug is necessarily formed.

With such an arrangement it will be apparent that immediately after ignition for any one cylinder occurs, the cylinder moves out of communication with the spark plug, leaving in the ignition pocket a charge of highly compressed spent gas. When the succeeding cylinder comes into communication with the ignition pocket, the spent combustion gases trapped in the ignition pocket at a pressure which may be several times compression pressure, expand into the compression space of the cylinder and contaminate the

fresh charge in the cylinder, particularly in the zone adjacent the ignition device. Turbulence may cause sufficient mingling of the gases to get some of the ignitable fresh charge to the vicinity of the point of ignition, but the time of communication between the igniting device and the cylinder is so short that this cannot in all cases be depended upon and the condition arising from the spent gases trapped in the ignition pocket may result in irregular firing as well as the disadvantages arising from dilution of the fresh gas charge with the spent gases.

In order to eliminate this difficulty, the ignition pocket is vented between times of communication with different cylinders and for the sake of simplicity of construction this is advantageously accomplished by means of a constantly open vent passage of small area which places the ignition pocket in communication with a zone of low pressure, preferably venting the pocket directly to atmosphere.

Referring now more particularly to Fig. 5, the venting of the ignition pocket is accomplished by means of a special type of spark plug. In this construction the plug 82 is seated in the bore 68 in the usual manner, the plug being of usual construction comprising an outer threaded metal shell 84 carrying an electrode 86 and a central core 88 carrying an electrode 90. Inwardly of the electrodes the inner portion of the bore and the cavity within the plug together form an ignition pocket indicated generally at 92 in which it will be evident that combustion gases will be trapped after a cylinder passes out of communication with the port 12.

According to the present embodiment of construction the outer shell 84 of the plug is drilled to provide a small diameter vent passage 94 which places the ignition pocket in communication with the atmosphere surrounding the valve member.

With this passage provided, it will be apparent that the pressure within the ignition pocket will be relieved during the time after the cylinder which has just been fired passes out of communication with the pocket and the time when the next cylinder comes into communication with it. Consequently, when the next cylinder comes into communication with the pocket the compression pressure in the cylinder will serve to force fresh gases past the electrodes, thus insuring the presence of an ignitable mixture at the proper place when ignition occurs. A very slight loss of fresh gas charge may occur through the vent passage 94, but it must be remembered that the ignition pocket and consequently the vent passage is in communication with the cylinder for only an extremely short space of time at the instant of ignition so that the loss of fresh gas through the vent passage will be so small as to be practically negligible.

The vent passage does not necessarily have to be placed in the plug and in many instances it may be desirable to arrange it so that a plug of standard construction may be employed.

Such an arrangement is shown in Fig. 6 in which the vent passage 94a is formed in the wall of the valve member and a plug 82a of standard construction is used. It will be evident that the passage 94a will vent the ignition pocket 92, and while with this construction the path of outward flow of the gases through the vent passage when a cylinder comes into communication with the pocket is not past the electrodes of the plug, the presence of fresh gas at the electrodes is never-

theless insured. The reason for this is that because of the reduction in pressure resulting from the flow of the trapped gases through the vent passage, the pressure in the ignition pocket 5 will be lower than compression pressure when the next cylinder comes into communication with the pocket and any spent gas at low pressure that may remain in the cavity of the spark plug will be compressed by the cylinder charge into the inner part of the spark plug cavity, thus permitting the fresh charge to reach the electrodes, which is all that is required.

From the foregoing it will be apparent to those skilled in the art that many structural changes may be made in the forms of apparatus hereinbefore described by way of example, without departing from the principles of the invention, some of which may be employed to the exclusion of others.

It is accordingly to be understood that the invention embraces within its scope all forms of construction falling within the scope of the appended claims when they are construed as broadly as is consistent with the state of the prior art.

What is claimed is:

1. A bi-rotary engine including a crankshaft, a cylinder bank and a valve member, all of said parts being mounted to have relative rotary movement with respect to each other, said valve member having a series of peripherally spaced inlet ports and said cylinder bank including a plurality of cylinders having ports at their working chamber ends positioned to come into and out of communication with the ports in the valve member due to relative rotary movement between the cylinder bank and the valve member, whereby to admit fluid to each of said cylinders a plurality of times during each revolution of the cylinder bank relative to the valve member, and a control member located between said cylinders and said valve member, said control member having a series of ports formed therein corresponding in number to the number of inlet ports in the valve member and correspondingly spaced, and said control member being adjustable relative to the valve member to alter the timing of admission of fluid to the cylinders through said ports.

2. A bi-rotary engine including a crankshaft, a cylinder bank and a valve member, all of said parts being mounted to have relative rotary movement with respect to each other, said valve member having a series of peripherally spaced inlet ports and said cylinder bank including a plurality of cylinders having ports at their working chamber ends positioned to come into and out of communication with the ports in the valve member due to relative rotary movement between the cylinder bank and the valve member, whereby to admit fluid to each of said cylinders a plurality of times during each revolution of the cylinder bank relative to the valve member, and a control member located between said cylinders and said valve member, said control member having a series of ports formed therein corresponding in number to the number of inlet ports in the valve member and correspondingly spaced, the ports in the control member having less peripheral extent than the corresponding ports in the valve member, and said control member being adjustable relative to the valve member to alter the timing of admission of fluid to the cylinders through said ports.

3. A bi-rotary engine including a crankshaft, a cylinder bank and a valve member, all of said

parts being mounted to have relative rotary movement with respect to each other, said valve member having a series of peripherally spaced inlet ports and a series of peripherally spaced exhaust ports alternating with the inlet ports and said cylinder bank including a plurality of cylinders having ports at their working chamber ends positioned to come into and out of communication with the ports in the valve member due to relative rotary movement between the cylinder bank and the valve member, whereby to admit fluid to and exhaust fluid from each of said cylinders a plurality of times during each revolution of the cylinder bank relative to the valve member, and a control member located between said cylinders and said valve member, said control member having a first series of peripherally spaced ports located to register with the inlet ports in said valve member and a second series of peripherally spaced ports located to register with the exhaust ports in said valve member, and said control member being adjustable relative to the valve member to alter the timing of gas flow to and from said cylinders through said ports.

4. A bi-rotary engine including a crankshaft, a cylinder bank and a valve member, all of said parts being mounted to have relative rotary

movement with respect to each other, said valve member having a series of peripherally spaced inlet ports and a series of peripherally spaced exhaust ports alternating with the inlet ports and 5 said cylinder bank including a plurality of cylinders having ports at their working chamber ends positioned to come into and out of communication with the ports in the valve member due to relative rotary movement between the cylinder bank and the valve member, whereby to admit fluid to and exhaust fluid from each of said cylinders a plurality of times during each 10 revolution of the cylinder bank relative to the valve member, and a control member located between said cylinders and said valve member, said control member having a first series of peripherally spaced ports located to register with the inlet ports in said valve member and a second series of peripherally spaced ports located to register 15 with the exhaust ports in said valve member, said first series of ports in said control member having less peripheral extent than the inlet ports in the valve member with which they respectively register, and said control member being adjustable relative to the valve member to alter the timing of gas flow to and from said cylinders through said ports.

IGNAC SKLENÁR.
